HINGE FOR DOORS

Giuseppe L. Cerami, Brooklyn, N. Y.

Application July 5, 1935, Serial No. 29,985

6 Claims. (Cl. 16—183)

This invention relates to hinges and has special reference to a hinge for doors which swing in both directions from closed position.

One important object of the invention is to provide a novel construction of hinge having an improved arrangement of springs for holding a door normally closed.

A second important object of the invention is to provide a novel hinge arrangement which may be used as a door to a frame side or one leaf of a folding door to another and which may be used for either single and double doors.

A third important object of the invention is to provide a hinge of this class having novel means to regulate the closing effect of the springs of the hinge so that the same hinge may be used for both light and heavy doors.

A fourth important object of the invention is to provide a novel form of such hinge arranged to be locked in both opened and closed positions.

A fifth important object of the invention is to provide a hinge of this type in which the door may be held open at any desired angle.

With the above and other objects in view, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a partial sectional view showing the device installed in a door and door-frame with the door in closed position.

Figure 2 is a similar view with the door partly open.

Figure 3 is a front elevation of the hinge.

Figure 4 is a side elevation of the hinge with one side of the casing removed.

Figure 5 is a rear elevation of the casing.

Figure 6 is a view similar to Figure 4, but with the parts in the position assumed when the door is at right angles to its closed position.

Figure 7 is an enlarged section on the line 7—7 of Figure 4.

Figure 8 is an enlarged section on the line 8—8 of Figure 3.

Figure 9 is an enlarged section on the line 9—9 of Figure 4.

Figure 10 is an enlarged detail showing a certain door locking latch used herewith.

Figure 11 is a side view of one of the cam arms used herein.

Figure 12 is an edge elevation of the cam arm.

Figure 13 is a detail showing a certain wedge for releasing a pawl used herewith.

In the embodiment here shown there is provided a casing 10 adapted to be housed in a door frame F having a face plate 11 fixed to one side plate 12 of the casing, the other side plate 13

being removable. In this casing is a frame having sides 14 and, at its front a series of hinge eyes 15. Above and below the frame there is provided the guide and pivot pins 16 which are fixed to the plate 12 and these pins are provided with roller sleeves 17 between which the frame moves. These pins are bored and threaded to receive the fastening screws 18 of the plate 13.

Pivoted to the upper and lower parts of the frame are cam levers 19 which each have a cam surface 20 bearing against a roller sleeve 17. In closed position of the door these levers 19 have their inner edges parallel as in Fig. 4 and between these inner edges coiled compression springs 21 are mounted in the frame.

At 26 is a door plate adapted to be secured to the edge of a door and this plate lies against the face plate 11 when the door is closed. Through this door plate pass transversely slideable arms 27 carrying rollers 28 at their outer ends. A screw 29 serves to clamp the arms 27 in adjusted positions. Hinge eyes 30 are fixed to the door plate and extend between the eyes 15, a hinge pin 31 passing through these eyes in the usual manner. The plate 11 is slotted at 32 to permit movement of the frame in and out of the casing.

As thus constructed the swinging of a door D to open the same causes the door plate 26 to rock on one of the rollers 28 as a fulcrum. This moves the frame outwardly in the casing which causes the arms 19 to swing toward each other by the action of the cam surfaces 20 on the roller sleeves 17. This compresses the springs 21 which thus resist opening movement of the door. When the door is released the springs 21 force these cam arms apart and the action of the arms on the roller sleeves 17 serves to draw the frame in and swing the door to closed position.

In order to lock the door in fully opened and in closed positions there is provided on the door plate a vertically movable slide 33 access to which may be had by cutting a suitable finger hole (not shown) in the door D. This slide is held in adjusted position by a spring 34. The slide carries a hook arm 35 which passes through a slot 36 in the plate 11 when the door is closed. A latch 37 is pivoted to the plate 11 and extends below the hook arm (see Fig. 10). The latch 37 may be moved into and out of engagement with the hook arm by a pin 38 passing through a slot 39 in the plate 11 and, when engaged therewith, locks the door in closed position. To lock the door in open position, the slide 33 is provided with a latch arm 40 which, when the door is fully open, may be moved by the slide into a notch 41 formed in the upward edge of the frame. When thus engaged the frame cannot move inwardly of the casing so that the door cannot close.

In order to latch the door in desired open po- 60

sition there is provided at the lower part of the casing a ratchet bar 42 which is connected at 43 to the door plate in the same manner as the frame is connected to the door plate so that the frame and ratchet bar move in unison. A plunger pawl 44 passes through the casing to engage this ratchet bar and this pawl is carried by a leaf spring 45 attached at one end to the casing and having its other end adjacent the face plate so that the free end of the spring may be moved to draw the pawl out of engagement by means of a wedge member 47 slideable on the face plate and operated by a pin 48 extending through said face plate. By this means, as the door opens the ratchet will move beneath the pawl and, unless the latter is held out of engagement it will ride over the ratchet teeth and, when the door is released, hold it in the desired position. Of course, when the pawl is disengaged the door will close.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a hinge, a casing having a face plate, a frame slideable inwardly and outwardly of said casing through said face plate, a door plate, means carried by the door plate and pivotally connected to said frame, said door plate being arranged to rock on said face plate whereby to move the frame in the casing, a pair of levers each pivoted at one end in said frame to swing toward and from each other, springs between said levers urging them apart, said levers having cam surfaces on the sides opposite the springs, and camming means fixed to the casing and engaging said cam surfaces to force the levers together and compress the springs as the frame is moved outwardly of the casing.

2. In a hinge, a casing having a face plate, a frame slideable inwardly and outwardly of said casing through said face plate, a door plate, means carried by the door plate and pivotally connected to said frame, said door plate being arranged to rock on said face plate whereby to move the frame in the casing, a pair of levers each pivoted at one end in said frame to swing toward and from each other, springs between said levers urging them apart, said levers having cam surfaces on the sides opposite the springs, camming means fixed to the casing and engaging said cam surfaces to force the levers together and compress the springs as the frame is moved outwardly of the casing and to move the frame inwardly of the casing when the free ends of the levers are forced apart by the springs.

3. In a hinge, a casing having a face plate, a frame slideable inwardly and outwardly of said casing through said face plate, a door plate, means carried by the door plate and pivotally connected to said frame, said door plate being arranged to rock on said face plate whereby to move the frame in the casing, a pair of levers each pivoted at one end in said frame to swing toward and from each other, springs between said levers urging them apart, said levers having

cam surfaces on the sides opposite the springs, camming means fixed to the casing and engaging said cam surfaces to force the levers together and compress the springs as the frame is moved outwardly of the casing, and manually operable means adapted to engage the pivotal connection between the door plate and frame to lock said pivotal connection against pivotal movement.

4. In a hinge, a casing having a face plate, a frame slideable inwardly and outwardly of said casing through said face plate, a door plate, means carried by the door plate and pivotally connected to said frame, said door plate being arranged to rock on said face plate whereby to move the frame in the casing, a pair of levers each pivoted at one end in said frame to swing toward and from each other, springs between said levers urging them apart, said levers having cam surfaces on the sides opposite the springs, camming means fixed to the casing and engaging said cam surfaces to force the levers together and compress the springs as the frame is moved outwardly of the casing, a ratchet bar arranged to move with said frame, a spring pressed pawl carried by the casing to engage the ratchet bar to hold the frame against inward movement, and manually operable means to release said pawl from the ratchet bar and to hold it in released position.

5. In a hinge, a casing having a face plate, a frame slideable inwardly and outwardly of said casing through said face plate, a door plate, means carried by the door plate and pivotally connected to said frame, said door plate being arranged to rock on said face plate whereby to move the frame in the casing, a pair of levers each pivoted at one end in said frame to swing toward and from each other, springs between said levers urging them apart, said levers having cam surfaces on the sides opposite the springs, camming means fixed to the casing and engaging said cam surfaces to force the levers together and compress the springs as the frame is moved outwardly of the casing, a ratchet bar arranged to move with said frame, a spring pressed pawl carried by the casing to engage the ratchet bar to hold the frame against inward movement, manually operable means to release said pawl from the ratchet bar and to hold it in released position, and manually operable means adapted to engage the pivotal connection between the door plate and frame to lock said pivotal connection against pivotal movement.

6. In a hinge, a casing having a face plate, a frame slideable inwardly and outwardly of said casing through said face plate, a door plate, means carried by the door plate and pivotally connected to said frame, said door plate being arranged to rock on said face plate whereby to move the frame in the casing, a pair of levers each pivoted at one end in said frame to swing toward and from each other, springs between said levers urging them apart, said levers having cam surfaces on the sides opposite the springs, camming means fixed to the casing and engaging said cam surfaces to force the levers together and compress the springs as the frame is moved outwardly of the casing, adjustable arms mounted in the door plate to slide transversely of the plate, rollers mounted in the outer ends of said last arms and resting on the face plate to form fulcrums for the door plate, and means to hold the adjustable arms in adjusted positions.

GIUSEPPE L. CERAMI.
